Primary Examiner—Kay H. Chin**[57] CLAIM**

The ornamental design for a oxygen carrier attachment for walkers, as shown and described.

DESCRIPTION

FIG. 1 is a perspective view of an oxygen carrier attachment for walker showing my new design, the broken lines are for illustrative purposes only and form no part of the claimed design;

FIG. 2 is a side elevational view thereof;

FIG. 3 is a top plan view thereof;

FIG. 4 is a side elevational view thereof in exploded condition;

FIG. 5 is a front view of the face plate;

FIG. 6 is a front view of the bracket;

FIG. 7 is a side elevational view of the bracket;

FIG. 8 is a sectional view of the face plate along the line 8—8 of FIG. 5; and,

FIG. 9 is a bottom view of the bracket.
